Patented Dec. 30, 1924.

UNITED STATES PATENT OFFICE.

GEORGE M. DUNLAP, OF CHICAGO, ILLINOIS.

RADIATOR SHUTTER.

Application filed February 8, 1924. Serial No. 691,489.

To all whom it may concern:

Be it known that I, GEORGE M. DUNLAP, a citizen of the United States, residing at Chicago, in the county of Cook and State of Illinois, have invented a certain new and useful Improvement in Radiator Shutters, of which the following is a specification.

This invention relates to devices for regulating the flow of air through the radiator 10 of an automobile. Specifically, it is a shutter applicable to the front end of such a radiator, equipped with means operable from the dash of the automobile for controlling the different positions of the moving 15 parts of the shutter, and, consequently, the amount of air admitted.

The invention consists in means very easily and cheaply constructable and applicable to the front of an automobile radiator, which is very efficient in operation and is not readily liable to get out of order.

Particularly, the invention consists in the application of two plates covering substantially the end of the radiator, equipped with 25 a plurality of air admitting perforations, one of the plates being slidable across the face of the other plate whereby a greater or less number of perforations in the respective plates can be brought into or out of 30 register with each other, thereby controlling the admission of air to the radiator. The invention further consists in many features and details of construction which will be hereafter more fully set forth in the specification and claim.

Referring to the drawings in which like numerals designate the same parts throughout the several views:

Figure 1 is a front view of a radiator 40 equipped with mechanism of this invention, the parts of the shutter being in the normal full open position in which a maximum quantity of air is admitted to the radiator.

Figure 2 is a sectional detail view on the 45 irregular line 2-2 of Figure 1.

Figure 3 is a rear view of the shutter mechanism, as shown in Figures 1 and 2, as sold in commerce apart from the radiator.

Figure 4 is a changed position view of the 50 mechanism of Figure 3 in which the shutter is closed.

The shutter mechanism of this invention, designed to be sold as a separate article of equipment, apart from an automobile and 55 applied thereto at the will of the user, consists generically of an outer or face plate 10,

provided with suitable bolts 12, 13, 14 and 15 for attachment of the shutter mechanism to the radiator 16 of the automobile, said plate 10 having pivoted to it preferably at one corner and upon one of the bolts, as 14, a second or shutter plate 18, movable between the full open position of Figures 1-3 and the closed position of Figure 4, the two plates 10 and 18 being respectively provided with 60 sets of perforations 20 and 22 which register with each other when the parts are as shown in Figures 1 and 2 and which are out of register with each other when the parts are in the closed position of Figure 4. The 70 movable or inner plate 18 is normally held in the open position of Figure 3 by suitable spring mechanism, specifically the spring 24, attached at one end to the bolt 15 and at the other end to a lug 26 or plate 18. 75

In the particular embodiment of the device here illustrated, the spring 24 is so positioned that it rocks the plate 18 in a clockwise direction until stopped by engagement of the lower side of a notch 28 in the top of the plate on the under side of a washer 30 of bolt 12 and the engagement of the vertical side 32 of a notch 34 in the lower left hand corner of the plate 18 on a washer 36 on bolt 13. The plate 18 is manually movable from the normal or open position of Figures 1-3 to the closed position of Figure 4 through the agency of a cord or cable 38 attached to the lower edge of plate 18 at a point suitably remote from pivot bolt 14, 90 said cord leading thence over suitable pulleys 40 and 42 to handle 44 extending through the dash 46 of the automobile. The lower edge of the inner portion of this handle 44 is provided with suitable notches 95 48 adapted to selectively fit over the latch plate 50 bordering the perforation 52 in the dash 46 through which the handle member 44 passes. By adjusting selected ones of these notches 48 on the plate 50, the operator can vary the position of the plate 18 between the full open position of Figures 1-3 and the full closed position of Figure 4 to thereby provide varying sized passages through the complete shutter mechanism. 100 105

It has been found in actual practice that by the construction described, very close regulation of the amount of air admitted to the radiator can be obtained; that because of the simplicity and small number of parts in the device, there is little, if any, danger of failure in successful operation. 110

Attention is called to the fact that by placing the pivot bolt 14 at one side of the plates 10 and 18, specifically at one corner of the substantially rectangular plate shown, 5 and by providing a large number of perforations 20 and 22 in the respective plates, a very fine gradation in the volume of air admitted through the device is obtained.

Having thus described my invention, what 10 I claim as new and desire to secure by Letters Patent is:

In mechanism of the class described, a plate provided with a plurality of perfora-

tions, a second parallel plate provided with corresponding perforations registering in one position with the perforations in the first plate, means at one edge of the plates so pivoting the plates together that the second plate may be moved across the first to positions where more or less of the perforations of the two plates are in register thereby controlling the aggregate passage of air through the device. 15 20

In witness whereof, I have hereunto subscribed my name.

GEORGE M. DUNLAP.
